ATTORNEY

UNITED STATES PATENT OFFICE.

WILLIAM W. HAYDEN, OF NEWARK, NEW JERSEY.

DESIGN FOR A HANDLE FOR CUTLERY, &c.

SPECIFICATION forming part of Design No. 21,810, dated August 30, 1892.

Application filed July 20, 1892. Serial No. 440,678. Term of patent 3½ years.

To all whom it may concern:

Be it known that I, WILLIAM W. HAYDEN, a citizen of the United States, and a resident of Newark, in the county of Essex and State 5 of New Jersey, have invented and produced a certain new and original Design for a Handle for Cutlery, of which the following is a specification.

Reference is to be had to the accompanying 10 drawing, forming a part of this specification, and in which the figure illustrates my newly-designed handle for cutlery and other articles.

My invention consists of a design for a handle 15 for cutlery or similar articles.

The handle A at its edges displays the outward curves *a a* and *b b*, which latter join the small scrolls or projections *c c*, between which appears the rounded end projection *d*. It also 20 shows the inward curves *e e* and *f f*. The

projections *c d* are ornamented with leaves *g* and flower *i*, and at the side curves *b b* appears the leaf ornament *j*, which reaches from curve to curve and shows a flower *j'* on the enlarged portion of the handle and a group or 25 spray of blossoms *j''* at and below the center of the handle. Another leaf ornament *k* appears at the lower part of the handle, which, like the ornament *j*, wraps around the edge, and it terminates in broad leaf *k'* at the point 30 of the handle and in a leaf and scroll *k''* at the opposite side.

What I claim is—

The design for a handle for cutlery, substantially as herein shown and described.

WILLIAM W. HAYDEN.
